MACHINE FOR SORTING, COUNTING, AND
PACKING COINSSiegmond Chiger, Berlin, Germany, assigner to
G. Z. M. Patentverwertung Aktiengesellschaft,
Clarus, SwitzerlandApplication July 11, 1929, Serial No. 377,531,
and in Germany November 7, 1928

12 Claims. (Cl. 93--2)

My invention relates to a coin sorting, counting and packing machine, in which the necessary tubular containers which are to hold the coins to be packed are made from a strip of paper before or while the coins, for the purpose of sorting out the smaller coins, are moved over holes of less diameter than the particular coins to be packed, and in which a counting device after a predetermined number of coins have been sorted automatically brings the rotatable coin-pusher to rest, thereupon closing the upper end of the tubular container which then is dropped through a trap, whereby simultaneously another counting device is actuated. Meanwhile, the counting device first referred to brings the rotatable coin-pusher again into operation, and the cycle of operations described is repeated.

The coin sorting, counting and packing machines now used have the disadvantage that as the sorting holes are provided in the bed plate, the machine can be used for only one kind of coin, and in the event of the coins being of equal size, thickness and weight, it is impossible to sort them out, and after the sorting, during the counting, the coins do not positively operate the counting gear, resulting in errors.

By the present invention the aforesaid disadvantages are obviated in that the test and discharge holes are not arranged in the bed plate, but in slides whereby the machine is rendered suitable for different kinds of coins. Above the discharge hole is provided a magnet, the object of which is to sort coins of equal size according to their magnetic properties. For instance, German fifty-pfennig coins are of the same size as German two-pfennig coins and are composed in part of magnetic metal, whereas the two-pfennig coins are non-magnetic. Now if fifty-pfennig coins are to be counted by the counting mechanism, they will be attracted by the magnet and counted while passing over the discharge hole, whereas the two-pfennig coins, because of their non-magnetic composition will drop through the discharge hole and thus become separated.

In the accompanying drawings, showing by way of illustration one embodiment of my machine, Fig. 1 is a sectional elevation of the same, Fig. 2 a plan view, Fig. 3 a sectional elevation, the upper portion showing the mechanism manufacturing the tubular containers and the lower portion a detail of the sorting, counting and packing machine; Fig. 4 is a plan view of Fig. 3, Fig. 5 an elevation of the spindle, on which a tubular container is formed, Fig. 6 a cross-section of the same, Fig. 7 a view of the

spring-controlled ledge in the spindle, and Fig. 8 a cross-section of the same. Fig. 9 shows the paper strip.

Figures 10, 11 and 12 are detail views of the means for forming the tubular containers and 60 for feeding the same to the packing device;

Figure 13 is a vertical section through a portion of the device shown in Figure 4, viewed from the right in said figure;

Figures 14 and 15 show, respectively, in elevation and axial section the means for producing the bottom part of the tubular containers;

Figure 16 is a partial vertical section of the counting wheels shown in Figures 1 and 2.

1 is the tubular container which is filled with 70 coins indicated at 2 to be sorted, counted and packed. The receptacle rests on the base-plate 3, on which a disc 4 equipped with two or more pushers 5 is rotatably mounted. Each pusher 5 is bevelled or hollowed out on one side so 75 that it will press the coin against the side wall of the base-plate 3 during the rotation of the disc 4. Base-plate 3 is provided with one or more apertures 7 and 8, the apertures 8 being of smaller diameter than the apertures 7. Above 80 the disc 4 is a stationary cover plate 9 to which are attached the pressure springs 10 and 11 which are centrally disposed respectively over the two apertures 7 and 8. On the bed-plate 31 (Figure 85) is rotatably mounted the paper roll 32 (Figure 4) and on the shafts 33 and 34 the paper feed-rolls 35 and 36. On the shaft 34 of the roll 36 bears the spring 37 whereby roll 36 is held in contact with roll 35. Thus, the strip of paper passing between the two rolls 35 and 36 is moved 90 along, as these rolls rotate. The roll 36 is provided with a segmental flange or flanges 35a adapted by contact with the roll 36 to separate roll 36 from roll 35, whereby, as will be described further on, the feeding of the paper strip 95 is interrupted.

The roll 35 is provided at its lower end with a cam disk 38a (Figure 13) the cam groove 38 of which is engaged by a pin 39 on one of the arms of a two-arm lever 39, pivoted at 40. On the other arm of lever 39 is provided a pin 43 engaging the knife 44 (Figure 13) which cooperates with the fixed knife or cutting blade 45. On the spindle 33 is mounted a toothed wheel 46, with which meshes the sector 47 mounted on a spindle 48 which also carries a cam 49 and on its lower end the main drive wheel 50. A pin on a roller 51 which is held in a rod 52 engages with cam 49. On rod 52 is mounted 110

a ring 103 with a spring 104 located above the same.

105 is a plate which is drilled at 106 to receive a bearing 106a of a spindle 107 which is provided with a slot 108 in which is inserted a spring controlled ledge 109. A sleeve 110 provided with a slot 111 and rigidly secured to the bearing 106a surrounds spindle 107.

The lower portion of the sleeve 110 is guided in 10 a circular recess of the disk 112. Below the latter, in the base-plate 81, is a hole into which enters a discharge tube 113. The disk 112 has four radial guide grooves, in which move bars 114 having pins 114a engaging the cam grooves 115a of a cam-disk 115 (Figures 14 and 15). The latter is rotatably mounted in the base-plate 81 and is provided with a toothed rim 116 meshing with the sector 117. If the latter is rotated as will be described further below, the 15 cam-disk 115 will be rotated with the result that the bars 114 are moved by means of the pins 114a guided in the cam grooves 115a. Because of the special arrangement of the loops distributed over the cams 115a, the bars 114 are 20 successively moved inwards, to perform certain functions described further down. The sector 117 is mounted on a shaft 118, on which shaft is also mounted, above said sector, a toothed wheel 119, which meshes with sector 97. On the 25 shaft 118, there is further mounted a toothed sector 120, meshing with the toothed wheel 121 rotatably mounted on shaft 122. The toothed wheel 121 meshes with a wheel 123 connected with the spindle 107.

30 A ring 124 is, by means of a pin 125, guided in the slot 111 of sleeve 110 and by said pin is connected with a strip-off ring 126 which moves on the spindle 107 within the sleeve 110. Moreover, the ring 124 is provided on its periphery with a pin 127 engaging a slot 128 of the lever 129. The latter is pivotally mounted on the wall 131 and has a second slot into which enters a pin 130 provided on the rod 102 so that upon the latter being raised, the ring 124 likewise is 35 raised.

The paper strip 82, on its way from the knives 94, 95 to the sleeve 110 is guided in a guide-way 132 formed by two vertically arranged sheet metal pieces.

40 A toothed wheel 80 mounted on spindle 51 (Figs. 1 and 2) meshes with the driving wheel 99.

Above the lower bed plate 32 and on spindle 55 33 is mounted the tubular container plate 34 which rests on the adjustable table 35 arranged beneath it. On the under side of this table 35 the same has formed integral therewith a tube 36 provided with teeth 37 meshing with the driving wheel 38. The tube 36 rotates in the bearing 39. The driving wheel 38 rotates on the spindle 40 on which is provided a lever 41 having a handle 42, which travels over the plate 43 in which are provided distance holes 44. A finger 46 secured to plate 34 engages with a longitudinal slot 45 on spindle 33, on the top of which is secured a wheel 47 which meshes with the toothed sector 48 mounted on the spindle 51 and driven by means of the coupling 24 (Figs. 1 and 2). A 50 disengaging pin 49a which operates the pawl 59 is provided on the toothed sector 48.

A segment 6 is cut out of the bed plate 3, into which cut-out portion is introduced a slide 6a containing the holes 7, 8. A cover 9 above the 55 disc 4 carries springs 10, 11 on its lower surface

above the holes 7 and 8. Magnet 9a is placed at the hole 8 where it is adapted to attract such coins passing over the hole 8 as are magnetic. Beneath the hole 7 is provided a discharge channel or chute 12. In the base-plate 3 is mounted the shaft 13 (Figure 2), on which are loosely provided the two toothed wheels 14 and 15, with which mesh the pinions 16 and 17 (Figure 16). The pinion 17 is driven by the intermediate wheel 18 mounted above it on shaft 78, which wheel on the passing of a coin is always turned. The pinion 17 transmits the rotation to the lower counting wheel 15, on which is secured the finger 26. The wheel 15 on its periphery is provided with a scale, for example from 1-50 or 1-100, permitting the number of the coins that have been counted to be read off. The finger 26, according to the divisions of the wheel 15, that is, after the counting of 50 or 100 coins, advances the diametrically opposite pinion 16 by rotating the same the distance of one tooth with the result that on the scale of the wheel 14 operated by said pinion 16, the number of the finished coin packages is counted. The pinion 17 is enclosed by a cover 20 (Figure 2) wherein is secured a pin 19, which after each advance snaps into a notch of the wheel 18, the purpose of said pin being simply to hold said wheel against rotation during the intervals between the successive step-by-step advances thereof. Above the pinion 16 there is mounted on the shaft 79 a feed wheel 21 engaged by the feed-lever 22 which is under the control of a spring and the end of which strikes the fork 23 thereby displacing the clutch 24.

In order that the latter may also be operated after only half the number of coins fed by the pusher 5 and collected in the discharge tube 12 has been counted, there may be provided on the pinion 15 a second finger 25 diametrically opposite the finger 26 (Figure 1), which also engages the pinion 16. By means of the two pressure rods 27 and 28, the finger 25 can be so displaced that it is moved into, or out of, engagement with the pinion 16. The two pressure bars 27 and 28 are always returned by the springs 29 and 30 to their original positions.

For holding the finger 25 in position, a pin 31 is provided which is under the control of a leaf-spring 31a on the under side of the pinion 15, which spring presses the said pin upwards.

The operation is as follows:

The tubular container 1 is filled with coins and as soon as the machine is put in operation (by means of a crank, or a spring, or electrically) the spindle rotates disc 4 so that each of the pushers 5 thereof will carry forward one of the coins 2 dropping onto the base plate 3 from container 1, first guiding it over the aperture 8 under pressure of the spring 11 testing the coins for diameter. Coins of smaller size drop through the aperture 8 and the tube underneath the same. If the coin is of the proper size, it is pushed over the aperture 8 toward the aperture 7 and because of the pressure of spring 10, it drops through tube 12 into the tubular container.

When the required number of coins (50, 100 etc.) have been counted, the finger 26 of the counting wheel 15 will move the wheel 21 thereby pressing the lever 22 against the lever 23 so that the coupling 24 will be engaged and the spindle 51 rotated, thereby rotating the wheel 80 secured to it and the sector 48. When the latter meshes with the wheel 47 and thereby advances the tubular container plate 34 to the extent of one

division bringing an empty tubular container in front of the discharge tube 12, the wheel 80 meshes with the wheel 99 and thereby drives the spindle 98 together with the sector 97 and 5 the cam disc 100 mounted on the spindle. Because of the engagement of sector 97 with wheel 96, the guide rollers 85 and 86 will be rotated and will feed the paper strip 82 disposed between them through the guideway 132 and between the knives 94, 95 into the slot 111 of sleeve 110. In the slot 108 (Figure 5) of the spindle 107 is inserted the ledge 109 (Figure 7) provided with recesses 109a containing springs 109b, which tend to move said ledge outward against the inner 10 wall of sleeve 110. The ledge 109 yields to this spring pressure as soon as the strip-off ring 126, which in Figures 10 and 11 is shown in its lower position, is raised within sleeve 110 above the upper end of the ledge. By this ledge, the paper 15 strip 82 entering through the slot 111 is gripped and moved along the inner wall of the sleeve 110, being wound around the bolt 107, the latter being rotated as follows:

By the engagement of the clutch 24, the driving connection between the shaft 51 and the driving shaft 51a is effected (Figure 2). The shaft 51 carries the wheel 80 which meshes with the wheel 99 (Figure 3). The latter is mounted on the shaft 98, which carries the driving sector 97 above the plate 105, which sector will mesh with the wheel 119 on shaft 118, when being rotated thereby driving the wheel 120, the intermediate wheel 121 and the wheel 123 mounted on the upper journal of the spindle 107, all said 20 wheels meshing with each other.

After the roll 85 has made a revolution, the segmental flanges 85a (Figures 3 and 4) force the spring-controlled roll 86 outward away from the roll 85, thereby interrupting the feeding of 25 the paper-strip 82. The cam disk 88a concentrically disposed relative to roll 85 and fixedly connected therewith, is provided with a cam-guide 88 (Figures 4 and 13) wherein is guided the bell-crank 89 by means of a pin 91. Because of the loop 88b of the cam-guide 88, the 30 lever 89 is rocked outward, so that the other end thereof is swung inward to move, by means of the pin 93, the knife 94 past the fixed knife 95 (Figure 13) thereby effecting cutting of the 35 paper sheet 82.

The sector 117 mounted on the spindle 118, rotates because of its engagement with the toothed rim 116, the cam disc 115 and produces, by means of the pins 114a an alternate advance 40 of the tongues 114, whereby the lower end of the tubular container projecting beyond the spindle 107 and the sleeve, will be turned over and a bottom formed for said tubular container. The lever 129 which was held raised by the cam 45 100 will then be released and forced down by the pressure of spring 104 lowering the ring 124 and the stripping-off ring 126 connected thereto, thus bringing the tubular container through the discharge tube 113 to the tubular container plate 34.

In order to enable the tubular container to be placed higher or lower, according to the number and thickness of the coins, the tubular container plate 34 is mounted on an adjustable table 50 35. When the lever 41 is brought above the plate 43 into the corresponding distance hole 44, the register pin 42 will snap in, and because of the rotary movement of lever 41, spindle 40 will be rotated and driving wheel 33 will be driven so that due to its engagement with the teeth 37 of

the tube 36, the latter will be raised thereby raising the table 35 which is connected to the said tube. Thus, the tubular container plate 34 will be likewise raised to the correct distance.

By means of the finger 46 secured to the plate 80 34 and engaging with the longitudinal slot 45 of the spindle 33, the spindle 33 will be rotated by the wheel 47 and the sector 48, the plate 34 will be rotated to a given extent and in this way, an empty tubular container will be advanced, while 85 the filled container pushed further along will drop out through the discharge tube.

In order to correctly and reliably close the tubular containers, the paper strip used for their manufacture is provided at the top and at the bottom, as shown in Fig. 9, with wire stitching at given distances. This ensures not only a steadier and more secure closing, but also makes it impossible to open a roll without it being noticed.

The lever 63 enables empty tubular containers to be ejected without operating the apparatus. When lever 63 is moved, a pawl 65 secured to it engages with the teeth 66 provided on the spindle 33 and moves the lever 69 through the pin 68 working in the recess 67. This lever 63 is only used however for preventing irregularities from being made during the movement of the counting wheels 14, 15 into the zero position. Setting to zero is brought about by turning the counting wheels by means of a crank which is inserted 100 into the slots 76, 77. When the slots are uncovered, the counting wheel can be moved during the working of the machine so that a smaller number of coins might be put into the tubular container and the latter could be counted as completely 105 filled. In order to make this impossible, there is provided a closing cap 73, the ends 74, 75 of which are situated over the slots 76, 77 and which prevent any access to them. The closing cap can be moved only by the operation of the lever 63 110 which, as has already been stated, will move the lever 69 and release the slots, but at the same time will move and discharge the tubular container which is being filled.

The pusher 5 brings a coin etc. which is fed 115 from the pile stacked in the tubular container 1, first over the hole 8, and if the coin is smaller than that which is to be counted, it will drop into the discharge channel, otherwise it will pass over the hole 8 towards the hole 7 through which it 120 will drop to pass through the discharge tube 12 into the tubular packing container. Before it leaves the hole 7, it will advance to the extent of one tooth the intermediate wheel 18 and thereby 125 the counting wheel 14, that is to say, it will positively count. These holes 7 and 8 are provided in the slide 6a which is interchangeable, and because of the difference in the dimensions of the holes 7, 8, it is possible to use one and the same machine for any coins, counters etc. When the 130 counting wheel 14 reaches the fiftieth or one-hundredth tooth (another number may, of course, be chosen according to requirements), that is to say, when 50 or 100 coins have been introduced 135 into the tubular container, the finger 25 or 26 will move the pinion 16, which in its turn will operate the lever 22 by means of the feed wheel 21, and as the fork 23 is secured to the end of the said lever, the coupling 24 will be brought 140 into engagement, and the spindle on which said coupling 24 is mounted will be caused to rotate. In order, however, to avoid the necessity of limiting the function beforehand to a given number, but, on the contrary, to render it possible to determine 145 at any time the number of coins to be 150

counted and packed in the same apparatus, the finger 25 is so mounted, that it can be switched in or out by means of the pressure rods 27, 28. Such fingers may, of course, be conveniently arranged also at other suitable points.

The clutch 24 is disconnected by the pin 49a provided on the sector 48 as follows:

After the clutch, due to the action of the lever 22 operated by the wheel 21, has been engaged 10 (Figure 2), it is held engaged by the pawl 50 which is controlled by the spring 50a. That is to say, the spring 50a rotates the pawl 50 to cause the outer end 50b thereof to engage behind the fork 23 thereby to maintain the clutch 24 engaged. 15 Now, if on the clockwise rotation of the toothed sector 48 the pin 49a comes to bear against the other bevelled end of the pawl 50, the latter is carried along in a counterclockwise direction 20 releasing the fork 23. The disengagement of the clutch 24 then takes place automatically under the action of the helical spring 24a.

The two different holes 7, 8 are provided for the purpose of eliminating smaller, that is to say, as a rule less valuable, coins, and of preventing them from getting into the tubular container. For exceptional cases, that is in the case of coins having different values but being the same diameter, thickness and weight, the magnet 9a is provided in the cover 9 directly next to the hole 30 to attract the coins of higher value thereby preventing them from falling through the hole 7 like the coins of smaller value. As the magnet 9a stops a short distance in front of the hole 8, the higher value coins will be released and drop 35 through the hole 8 into the tubular container provided for them.

I claim:

1. In a machine of the character described, coin packaging means comprising a sleeve having 40 a slot through which a sheet of wrapping paper is adapted to be introduced into the sleeve, a rotatable spindle within the sleeve, yieldable means carried by the spindle and urged constantly outwardly therefrom for cooperation 45 with the sleeve to grip the paper and form the same into a tube, means for folding the lower end of said tube to close the same, and means for transferring said tube from said sleeve to a position to receive the coins.

2. In a machine of the character described, means for forming a tube to receive coins to be packaged comprising a sleeve having a longitudinal slot through which a sheet of wrapping paper is adapted to be introduced into the sleeve, 55 a spindle rotatable within the sleeve, and yieldable paper gripping means carried by the spindle and urged constantly outwardly therefrom for cooperation with the sleeve whereby rotation of the spindle relative to the sleeve is effective to wind the paper into tubular form.

3. In a machine of the character described, means for forming a tube to receive coins to be packaged comprising a sleeve having a longitudinal slot through which a sheet of wrapping paper is adapted to be introduced into the sleeve, 65 a spindle rotatable within the sleeve, a paper gripping element in the form of a plate mounted in a slot in the spindle for cooperation with the sleeve to effect winding of the paper into tubular form by rotation of the spindle relative to the sleeve, and spring means for urging said plate outward to grip the paper.

4. In a machine of the character described, 75 means for forming a tube to receive coins to be packaged comprising a sleeve having a longi-

tudinal slot through which a sheet of wrapping paper is adapted to be introduced into the sleeve, a spindle rotatable within the sleeve, a paper gripping element carried by the spindle, yieldable means urging said element outward relative to the spindle so as to grip the paper, whereby rotation of the spindle relative to the sleeve is effective to wind the paper into tubular form, and means movable longitudinally of the spindle and by such movement being operable to depress said element to release the tube and to effect ejection of the tube from the sleeve.

5. The combination of elements as set forth in claim 4 in which the means to depress the paper gripping element and to effect ejection of the tube from the sleeve comprises a strip-off ring interposed between the sleeve and the spindle.

6. The combination of elements as set forth in claim 4 in which the means to depress the paper gripping element and to effect ejection of the tube from the sleeve comprises a strip-off ring interposed between the sleeve and the spindle, and in which longitudinal movement is imparted to said ring by a second ring slidably mounted on the outside of the sleeve and connected with the strip-off ring by a pin extending through the slot in the sleeve.

7. In a machine of the character described, tube forming and ejecting means having a fixed location, means rotatable relatively to said tube forming means to receive tubes ejected from said tube forming means, means for delivering coins to a formed tube supported on said rotatable means, means whereby rotation of said rotatable means permits delivery of the tubes from said latter means, and means to rotate said rotatable means intermittently to simultaneously bring a vacant tube receiving space on said rotatable means into position to receive a tube ejected from said tube forming means, to bring a tube into position to receive coins from said coin delivery means, and to bring another tube into which coins have been delivered to a position for delivery from said rotatable means.

8. The combination as set forth in claim 7 in which means are provided for moving the rotatable means axially to accommodate tubes of different lengths.

9. In a machine of the character described, a horizontally disposed non-rotatable table, a plate rotatably mounted on said table and provided with an annular series of spaced tube receiving openings, means for intermittently rotating said table through angles corresponding to the spacing of said openings, tube forming means having a fixed location above said plate, coin delivery means having a fixed location above said plate and so spaced from said tube forming means that when one of the plate openings is aligned with the latter means to receive a tube therefrom another opening having therein a tube previously formed and delivered thereto by the tube forming means is aligned with the coin delivery means to have coins supplied thereto, the table having an opening so located that another opening of the plate aligns therewith when other of the plate openings are aligned with the tube forming and the coin delivery means, respectively, to permit a previously filled tube to drop through the table.

10. The combination as set forth in claim 9 in which means are provided for vertically adjusting the table and the plate to accommodate tubes of different lengths.

11. In a machine of the character described,
